UNITED STATES PATENT OFFICE.

WILLIAM H. MCFADDEN, OF GREEN ISLAND, ASSIGNOR TO GEORGE B. CLUETT, BRO. & CO., OF TROY, NEW YORK.

DESIGN FOR A COLLAR.

SPECIFICATION forming part of Design No. 19,163, dated June 18, 1889.

Application filed December 29, 1888. Serial No. 294,982. Term of patent 7 years.

To all whom it may concern:

Be it known that I, WILLIAM H. MCFADDEN, a citizen of the United States, residing at the village of Green Island, Albany county, 5 and State of New York, have invented and produced a new and original Design for Apparel-Collars, of which the following is a specification, reference being had to the accompanying drawings, forming a part thereof.

10 Figure 1 is a view in perspective of my newly-designed collar. Fig. 2 is a side elevation of the same.

15 The leading feature of my design consists of a collar provided with the ordinary button-hole tabs, having each of the ends of the upright portion of the collar of convex or rounded outline, and an angular point depending outwardly and downwardly from the said convex or rounded extremity.

A A' are the angular points depending 20 downwardly and outwardly from the rounded extremities C C'. These rounded extremities form the end outlines of the upright portion of the collar and extend from the button-hole tabs to points E E' on the upper edge of the 25 collar.

What I claim is—

The design for an apparel-collar herein shown and described.

In testimony whereof I have hereunto set 30 my hand this 26th day of December, 1888.

WILLIAM H. MCFADDEN.
